RAILWAY TRAIN COMMUNICATION
SYSTEMPaul N. Bossart, Cheswick, Pa., assignor to The
Union Switch & Signal Company, Swissvale,
Pa., a corporation of Pennsylvania

Application April 3, 1936, Serial No. 72,605

31 Claims. (Cl. 246—8)

My invention relates to railway train communication systems, and particularly to railway train telephone systems.

The present application is a continuation-in-part of my copending applications, Serial No. 737,076, filed July 26, 1934, for Apparatus for railway train communication systems; and Serial No. 759,467, filed December 28, 1934, for Communication systems for railway trains.

10 A feature of my invention is the provision of novel and improved apparatus for railway train communication systems which is operative to transmit communication current along the trackway. A further feature of my invention is the 15 provision of novel and improved apparatus for systems of the type here involved wherewith line wires and other conductors which extend more or less parallel to the track rails are effective as a communication channel for conveying a 20 communication current along a railway track without it being necessary that the line wire be continuously near the track rails, such as over the top of a high cut or looping around some obstruction, and without physical connection between the rails and such line wire. Another 25 feature of my invention is the provision in systems of the type here contemplated of inductors mounted on a railway train for induction to the track rails of adjacent tracks and other 30 parallel conductors as well as to the rails of the track on which the train is traveling. A still further feature of my invention is the provision of apparatus wherewith a communication channel is made available for a train traveling on 35 any one track of a multiple track railway and which channel has a relatively low attenuation of the communication current at the distance equal to the length of an ordinary freight train. Again, a feature of my invention is the provision 40 of novel and improved apparatus operative to supply communication current to the rails from a location on a railway train by direct coupling. Other features and advantages of my invention will appear as the specification progresses.

45 I will describe certain forms of apparatus embodying my invention, and will then point out the novel features thereof in claims.

A train signaling system has been proposed in the United States application for Letters Patent Serial No. 450,135, filed May 6, 1930, by L. O. Grondahl for Electric train signaling systems, and in which systems the track rails in multiple 50 are utilized as a communication channel for transmitting communication current between a 55 location on a railway train and a remote loca-

tion. My present invention may be considered as an improvement on this Grondahl system.

In such systems, the communication current is preferably a modulated carrier current, such as, for example, a side band carrier telephone current. That two-way communication may be accomplished, each location is provided with equipment which consists of transmitting apparatus and receiving apparatus together with circuit means operative to effectively couple each apparatus with the track rails.

When the receiving apparatus of a location is made effective, an electromotive force is created therein in response to the communication current flowing in the track rails, the value of such 15 electromotive force being in accordance with the strength of the current in the rails.

When the transmitting apparatus of a location is rendered effective an electromotive force corresponding in frequency with the frequency 20 of the communication current is created in the rails adjacent the sending location, and as a result of such electromotive force, current flows in the rails in multiple in both directions from the point where such electromotive force is created. The attenuation of such current along the rails is dependent upon the rail to ground or ballast resistance, being relatively high when the ballast resistance is low and being relatively 25 low when the ballast resistance is high. Hence, such current creates along the rails in each direction from the sending location a zone of influence which is relatively strong near the sending location and becomes weaker at points distant from the sending location. I have found 30 that a communication current of the order of 8,000 cycles per second flowing in the track rails halves about every 275 feet at locations where the ballast resistance is of the order of 3 ohms per 1,000 feet of track with the result that the 35 attenuation of the current may, due to wet ballast and other unfavorable transmitting conditions, be of the order of 10^5 power in a mile of 40 track.

In accordance with my invention, transmission 45 of communication current from the point where it is supplied to the rails to a remote location where it is picked up from the rails is accomplished in part through the medium of line wires and other paralleling conductors disposed along 50 the railway, energy being transferred from the track rails to the line wires and other conductors adjacent the zone of relatively strong influence extending to each side of the sending location, and then being transferred from the line wires 55

and other conductors back to the track rails throughout adjacent stretches beyond said zone. According to my understanding of the operation, the electromotive force created in the track rails at the sending location is comparatively large and the current flowing in the rails near the sending location is correspondingly large. The rail current induces an electromotive force in adjacent conductors by virtue of the distributed mutual induction between the rails and the conductors. The current resulting therefrom in a line wire may not attenuate as rapidly as the original current in the rails with the result that at some distance away from the sending location the current in the line wire is the larger and induces an electromotive force in the track rails by virtue of the distributed mutual induction. This electromotive force produces a current in the rails which at that location is larger than the original current remaining in the rails. That is, adjacent the zone extending from the sending location and where the rail current is relatively large, energy is transferred to parallel conductors such as a line wire due to the distributed mutual induction of the rails to the line wire. This induction is effective to create an electromotive force in the line wire notwithstanding the line wire may not be continuously near the rails, there ordinarily existing sufficient stretches along such zone of influence where the rails and line wire are in effective inductive relationship. The electromotive force thus induced in the line wire sets up a flow of communication current in the line wire. The usual line wire is a relatively efficient conductor for such current and hence the attenuation of the current along the line wire is relatively small with the result that at the distance equal to the length of a long freight train the current flow in the line wire is relatively large compared with the communication current transmitted to such distant point through the rails alone. For example, the attenuation of an unloaded bare line wire is of the order of one per cent per mile. At such remote point, an electromotive force is induced in the track rails in response to the current flowing in the line wire due to the distributed mutual induction of the line wire to the rails, such induction being effective adjacent the stretches where the line wire is relatively near to the rails. This latter electromotive force induced in the rails sets up a flow of current in the rails in multiple which may be many times larger than the original current in the rails at such remote point. This induction from the line wire to the track rails takes place not only between the line wire and the rails of the track occupied, but also to the rails of each track of a multiple track railway. Furthermore, the usual telephone, telegraph and signal control wires function in this transfer of communication current without interference to the circuits in which they are commonly employed and where several such wires are available each adds to the sum total of the energy transferred. It will be understood, of course, that a line wire which functions only to transmit communication current may be erected if found desirable. Also, tuning devices may be associated with the line wire to increase the flow of communication current. Communication between a location on a train and a remote location consists, therefore, of several stages of energy transfer, namely; first, from the transmitting apparatus to the rails; second, induction from the rails to line wires and other parallel con-

ductors; third, induction from the line wires and other conductors to the rails of each track of the railway; and fourth, induction from the track rails to the receiving apparatus.

For a better understanding of my invention, reference may be had to the accompanying drawings in which Fig. 1 is a diagrammatic view of a communication system embodying my invention. Fig. 2 is a view partly diagrammatic and partly perspective showing inductors embodying my invention as preferably mounted on a vehicle of a railway train for inductively transmitting and/or receiving energy. Figs. 3 and 3a are diagrammatic views of apparatus on a railway train for directly coupling the transmitting apparatus with the track rails and which apparatus also embodies my invention. Fig. 4 is a diagrammatic view of circuits and apparatus at a location on a vehicle of a railway train wherewith both sending and receiving are accomplished by the inductors of Fig. 2. Fig. 5 is a diagrammatic view of circuits and apparatus at a location on a train where sending is accomplished by the apparatus of Fig. 3 or Fig. 3a, and receiving is accomplished by the inductors of Fig. 2. Figs. 6, 7, and 8 are diagrammatic views of apparatus for reducing the impedance of the line wire of Fig. 1. Figs. 9, 10, and 11 are detail views partly in section of a preferred manner of connecting the sending circuits of Figs. 3 and 3a with journal bearings of the respective vehicles, and for insulating the journal bearings to which connections are made from the associated journal boxes. Fig. 12 is a diagrammatic view showing the parallel connection of the sending circuits of Figs. 3 and 3a with the vehicle wheels to reduce the resistance of the circuits and to provide equal voltage on both track rails.

In each of the several views, like reference characters refer to similar parts.

Referring to Fig. 1, the reference characters 1a and 1b designate the track rails of a westbound track RT1, and 2a and 2b designate the track rails of an eastbound track RT2 of a double track railway. The reference character L designates a line wire such, for example, as a telegraph or a telephone wire usually present on a pole line along the right of way. The line wire L may be of any suitable size and material. It will be understood that line wire L may be a special wire mounted on the pole line along the railway tracks. The significant thing to be noted in connection with the line wire L is that due to construction conditions imposed upon a pole line along a railway, the distance between the line wire and the track rails varies, there being stretches where the line wire may be close to the track rails, say less than 30 feet, and other stretches where the line wire may depart several hundred feet from the rails. This condition is illustrated in Fig. 1 by the adjacent sections 33, 35, and 37, and distant sections 34, 36, and 38. That is to say, due to practical construction, the line wire along the railway track comprises successive stretches which are more or less alternately near to and far from the rails. Furthermore, there will be localities where the line wire is at one side of the tracks and other localities where it is on the opposite side. It will be understood, however, that my invention is not limited to a line wire having stretches that are near to and far from the track rails and it may be continuously near the track rails but the invention is

effective without special construction to bring the line wire close to the rails.

31 designates the rear vehicle of a railway train occupying the track RT1, and 32 designates the forward vehicle of the train. For example, 5 31 and 32 may be the caboose and locomotive, respectively, of a freight train, the intervening cars being omitted and indicated by a dotted line for the sake of clearness. For communication 10 between the caboose 31 and the locomotive 32, the caboose is equipped with transmitting apparatus TA capable of supplying a communication current, and the locomotive is equipped with receiving apparatus RA responsive to such communication current.

The transmitting apparatus TA and the receiving apparatus RA may each take different forms among them being the electron tube type, and each is here shown conventionally for the sake 20 of simplicity, since the specific structure of such apparatus forms no part of my present invention. For two-way communication between the caboose and locomotive, the caboose will also be equipped with receiving apparatus and the locomotive will be equipped with transmitting apparatus. The operation of the apparatus of Fig. 1 will be taken up after the relationship of the receiving apparatus RA, transmitting apparatus TA, and the line wire L with the track rails of tracks 30 RT1 and RT2; and the preferred arrangement of such transmitting and receiving apparatuses are described.

C1 and C2 of Fig. 2 are inductors mounted on a vehicle of a railway train on which communication equipment is installed. These inductors C1 and C2 may take different forms and are here shown as air core coils of relatively large central area and constructed to have a relatively low power factor, say, 0.5% at frequencies at the 40 order of 10,000 cycles per second. Fig. 2 illustrates how I would prefer to mount these inductors upon the caboose of a freight train, the two coils being mounted in a vertical plane on the roof of the caboose one on each side of the 45 cupola. It will be understood, however, that a single inductor placed on one side of the cupola may be used or the two inductors may both be mounted on the same side of the cupola. The inductors C1 and C2 may each consist of many 50 or only a fraction of a turn as desired.

The size and position of inductor coils C1 and C2 of Fig. 2 give relatively large mutual inductance to the track rails of the track occupied by the train. Furthermore, the mutual inductance of these inductors C1 and C2 to the rails of an adjacent track is relatively large since for 55 a vertical coil the maximum inductance to a conductor displaced to the side occurs when the vertical displacement of the coil is only a trifle 60 greater than the horizontal displacement. That is, the mutual inductance to a conductor displaced to the side is greatest when the coil is mounted at such a height that the angle with the horizontal plane made by a plane through the conductor and the center of the coil is about 65 45°. It will be clear from an inspection of Fig. 2 that the vertical displacement of the inductors C1 and C2 mounted on the roof of the caboose with respect to the rails of the tracks RT2 and 70 RT4 is about the same as the horizontal distance, assuming the usual 13 foot clearance between track centers is maintained. I have found that a coil of large central area mounted on a caboose roof as shown in Fig. 2 possesses mutual inductance to the rails of the track occupied by the 75

caboose of about the same order as an iron core coil of the same resistance mounted directly over the rail at approximately 6 inch clearance. I have also found that an inductor mounted relatively high on a vehicle possesses inductance to 5 the rails of an adjacent track of the order of 1 to 2 as compared to the inductance of such inductor with the rails of the track occupied. Again, the inductor coils C1 and C2 are in inductive relation with the line wire L located on a 10 pole line along the right of way. However, due to the distance to the line wire L and to the position of such line wire with respect to the horizontal plane of the inductors C1 and C2, their induction to the line wire is small compared with 15 their induction to the track rails and ordinarily may be neglected. With the line wire L brought close to the track and in an effective position, a current in the line wire in phase with such current in the rails adds its effect to that of the rail 20 currents. The inductors C1 and C2, when used for sending, induce an electromotive force in the metal body of the caboose which electromotive force is in the same direction as the electromotive force induced in the track rails. Hence, for 25 inductor coils mounted as shown in Fig. 2, the body of the caboose is an effective path in parallel with the track rails. Furthermore, with the inductors mounted above the body of a vehicle, the noise signal ratio when running is relatively 30 low, much less than the noise signal ratio of inductors mounted just above the track rails.

Consequently, the inductors C1 and C2 possess relatively high mutual inductance to the track rails of each of the tracks RT1, RT2, 35 RT3, and RT4; and due to their position they will induce, when current is supplied thereto, electromotive forces in the several track rails and in the body of the caboose which will produce currents that flow at any instant in the 40 same direction in the respective paths. Likewise, a current flowing in multiple in the several track rails and in the body of the caboose will induce electromotive forces in the inductors which add their effects. Due to construction 45 conditions imposed upon a pole line along a railway, a line wire will ordinarily possess little inductive relationship with these inductors, but a line wire when brought close to the track and in an effective position will possess mutual inductance with these inductors. To visualize this paralleling arrangement of the track rails with respect to the inductor coils, arrows have been 50 added to Fig. 2. It is clear, this relationship between the track rails and the inductor coils exists for trains occupying any one of the four tracks. For vehicles other than a caboose the inductor coils C1 and C2 would be mounted on the vehicle at approximately the same height and positions, for example, as they would be 55 mounted on the top at the rear end of a locomotive tender.

Sending circuits effective to supply communication current from train-carried transmitting apparatus to the track rails by direct coupling 65 are disclosed in Figs. 3 and 3a. Referring first to Fig. 3, the reference character V designates a vehicle of a railway train such as, for example, the caboose of a freight train and on which vehicle communication equipment is 70 mounted, the transmitting apparatus being indicated conventionally at TA. It is deemed sufficient for this application to point out that when the transmitting apparatus TA is rendered active, a communication current is sup- 75

plied to the primary winding 9 of an output transformer T_1 , the secondary winding 8 of which is interposed in a sending circuit that includes the wheels 4 and 5 at the opposite ends 5 of the caboose, and the track rails between these wheels, connection with the wheels being preferably made through their journal bearings. For reasons to shortly appear, the return portion of this sending circuit is run vertical at 10 one end of the caboose to the roof, above the roof to the opposite end of the caboose and then downward to the wheel at that end. A construction that I have found satisfactory for a sending circuit on a caboose of a freight train 15 will now be described, certain details of the construction being disclosed in Figs. 9, 10, 11, and 12. One terminal of the secondary winding 8 of the output transformer T_1 is connected with the journal bearing 80 (Figs. 9, 10 and 11) of wheel 5 by a flexible insulated conductor 6, connection to the bearing 80 being 20 made by means of a flat terminal lug 112 secured to the end of the bearing 80 by two screws 113 tapped into the bearing, and the flexible conductor 6 being carried through the wall 25 of the journal box JB by any convenient bushing. As shown in Fig. 12, there is a parallel connection 6a from conductor 6 to the journal bearing of the wheel 5a at the other end of the same axle. Such parallel connections are made 30 to the bearings at both ends of the axle to reduce the contact resistance between the bearings and the axle, and between the wheels and the rails, and to maintain the same voltage on both track rails. Connection from the other 35 terminal of the secondary winding 8 is taken over conductors 81 and 82 to the extreme left-hand end of the caboose, then vertically by conductor 83 to a point about 6 inches above the caboose roof, along one end of the caboose roof by conductor 84, conductor 85 over the cupola without exceeding existing clearances, conductor 86 along the other end of the roof, downwardly by conductor 87 at the extreme right-hand end of the caboose, conductor 88, and 40 flexible conductor 7 to the journal bearing of the wheel 4, the connection of flexible conductor 7 with the journal bearing of wheel 4 being the same as that described for connecting the flexible conductor 6 to the journal bearing 45 of wheel 5. The conductor 7 is provided with a parallel connection 7a (Fig. 12) to the journal bearing of the wheel 4a at the other end of the same axle to reduce the resistance of the 50 circuit and to assure the same voltage is applied to both track rails. It follows that with the transmitting apparatus TA of Fig. 3 made active, communication current flows in the track rails between the wheels 4 and 5 and a voltage 55 across this length of rails is created and which voltage is illustrated as E volts. As a result of this voltage E created along the rails between the opposite ends of the caboose, communication current flows in the rails in each direction from the caboose and returns through the ground path as illustrated by broken lines in Fig. 3. The current flowing in the rails adjacent the caboose is relatively large but diminishes in 60 value as the distance from the caboose is increased. This diminishing value of the current 65 is illustrated by arrows placed on Fig. 3. It will be apparent that due to such current a zone of influence extending in both directions from the caboose is established and which zone moves 70 along with the caboose and the influence of 75

which becomes less as the distance from the caboose becomes greater.

The important thing is to produce the maximum voltage along the track rails for a given power output of the apparatus TA. The voltage E depends upon two factors, the current flowing in the rails from wheels 4 to 5, and the impedance of the rails between the points of contact. Consequently, the remaining portion of the sending circuit outside of the rails should 10 be of low resistance. For this reason, the conductors 82, 83, 84, 85, 86, 87, and 88 are constructed of copper pipe, say one inch size. Because of skin effect, there is no need to have these conductors solid. This copper pipe also 15 provides a conductor having the desired mechanical strength. These conductors are insulated as indicated at 99 in any suitable manner from the metallic parts of the caboose. The other factor, impedance of the rails between 20 wheels 4 and 5, depends in part upon the length, and hence it is desirable to connect to the wheels furthest apart. The rail impedance is made up of resistance and reactance, the latter being many times the larger of the two factors at the 25 frequency of the communication current used. The inductive reactance depends upon the distance the return portion of the circuit is away from the rail, increasing neglecting end effects with the ratio logarithm of the distance to the 30 return portion of the circuit divided by the radius of the conductor used. It is clear that with the sending circuit constructed as described above, the return portion of the circuit over the roof of the caboose is removed as far as possible 35 from the track rails. As will appear hereinafter, the return portion of the sending circuit when carried far away from the track rails effects a further advantage since the current in the return portion of the circuit flows in the same 40 direction as the current in the rails beyond the caboose. Arrows have been added to Fig. 3 to visualize the direction of the current at an instant the voltage E is of the polarity indicated by the plus and minus signs.

In order to have as much current in the rails as possible, shunt paths from wheel 4 to wheel 5 should be avoided. One shunt path that might occur would be from the journal bearings through the journal boxes and body of the caboose. Current is prevented from flowing through such shunt path by insulating the journal bearings from the wedge which holds it in the journal box and from the journal box itself. Referring to Figs. 9, 10, and 11, the reference character 89 is the axle, a shoulder 90 being formed thereon to prevent the bearing 80 from working past the end of the axle. 91 is the iron wedge which goes between the bearing 80 and the journal box JB, the wedge 91 engaging the top of the journal box at 92 to prevent its moving outward. Bearing 80 has a collar 93 which extends up back of the wedge 91 so that the wedge cannot move inward. The bearing 80 is prevented from moving inward by the side projections 94 and 95 engaging opposing projections of the journal box JB. The above construction is that of standard practice. To insulate the journal bearing 80 from the wedge 91 and from the journal box JB, a sheet of insulation 96 is provided. This insulating sheet may be of any suitable material such as fiber and is formed to fit over the bearing 80, as shown in Fig. 11, covering the entire bearing area between the bearing and the wedge. The fiber sheet 96

45

50

55

60

65

70

75

is turned up over the collar 93, as shown in Fig. 10. To prevent the bearing 80 from touching the journal box at its projections 94 and 95, the fiber sheet is turned down, as shown at 97 and 98. It is thus seen that the bearing 80 does not make metallic contact to the journal box JB direct or through the wedge 91 which holds it in place. I have found that such insulation is easily installed and is effective. It follows that with the bearings for the wheels 4, 4a, 5, and 5a of the caboose insulated in the manner explained above, a shunt path from the journal bearings through the journal boxes and the body of the caboose is avoided, and substantially all of the current follows the path through the wheels and track rails. When the brakes are applied, there is a possibility of a shunt path through the brake rigging, but this occurs after the current is in the wheels which are in direct contact with the rails and such shunt path is of relatively high resistance.

Fig. 3a discloses a similar sending circuit applied to a locomotive. On the locomotive, a convenient place for housing the communication equipment is on the top of the rear end of the tender as indicated at EH. One terminal of the secondary winding 100 of an output transformer T3, the primary winding 101 of which is connected with the transmitting apparatus of the locomotive, is connected to conductor 102 which extends to the rear of the tender, thence by conductor 103 down the back of the tender and then by flexible conductor 104 to the journal bearing of the rear wheel 114 of the tender, connection of conductor 104 to the journal bearing being in the manner shown in Figs. 9, 10 and 11. The conductor 104 is provided with a parallel connection to the journal bearing at the other end of the same axle similar to that disclosed in Fig. 12 for conductors 6 and 7. Starting at the other terminal of the secondary winding 100, the circuit extends by conductor 105 supported above the tender side wall, flexible removable coupler 106 between the tender and locomotive, conductor 107 supported along the roof of the locomotive cab along the locomotive boiler by conductor 108 which when properly insulated may serve as a secondhand rail parallel to the original one, downward by conductor 109, around the boiler far enough back from the front end to be in the clear, and flexible conductor 110 to the bearing of the forward wheel 111 of the locomotive, there being provided a parallel connection to the bearing at the other end of the same axle. This circuit is preferably constructed as far as possible out of copper pipe similar to the sending circuit of the caboose and insulated from the metallic parts of the locomotive. It will be understood, however, that my invention is not limited to the use of copper pipe for these sending circuits and other conductors may be used if found desirable. It is clear that the locomotive sending circuit as described above possesses the desirable characteristics discussed for the sending circuit on the caboose.

It has been proposed for systems of the type here under consideration to modulate a carrier current with voice frequencies for telephoning, and to modulate the carrier by a single predetermined voice frequency for calling and code signaling. The receiving apparatus at each location is normally active and in circuit ready to receive a message from remote location at any time, but the transmitting apparatus at each location is normally inactive and is energized

and placed in circuit only during the sending of current from that location. To reduce noise and to provide selectivity, the receiving circuit may be sharply tuned to the single frequency which corresponds to the calling frequency. The tuning of the receiving circuit is, for telephoning, broadened for the reception of a band of frequencies of a width equal to the desired voice frequency range. For code signaling, the sending location sends impulses of the calling frequency in accordance with a prearranged code, the receiving circuit at the remote location being retained at its sharply tuned condition. To fix the ideas I shall assume that a band of voice frequencies extending from 600 cycles to 1800 cycles per second for telephoning is desired, the calling frequency is 800 cycles per second, a carrier of 7000 cycles per second is employed and single side band transmission is contemplated, the upper side band being transmitted. It follows that during telephone communication a band of frequencies extending from 7600 to 8800 will be transmitted and for calling and code communication the frequency will be 7800 cycles. It will be understood, of course, that my invention is not limited to these specific frequencies and other frequencies may be chosen.

The transmitting apparatus will ordinarily include a microphone, a generator of carrier current, means for modulating the carrier with frequencies corresponding to the voice impulses produced in the microphone, calling means operative to produce a frequency equal to the carrier modulated by the predetermined voice frequency, and a power amplifier for amplifying the out-going current to a relatively high energy level. The receiving apparatus will ordinarily include a high gain amplifier, a demodulator for reproducing the audio frequencies of the modulated carrier, an audio frequency amplifier, filters for suppressing frequencies outside the desired band, and a loudspeaker. The specific structure for such amplifiers, modulators, and demodulators forms no part of my present invention, and these devices will be referred to in the present description only insofar as it is necessary for the understanding of my invention. The inductor coils of Fig. 2 are effective to both send and receive energy and, hence, one embodiment of the invention will include the use of the inductor coils for both sending and receiving. A second embodiment of the invention will employ the sending circuits of Figs. 3 and 3a and the inductors of Fig. 2 for receiving. In Fig. 4, a preferred form of circuits and apparatus for employing the inductor coils for both sending and receiving is disclosed. In Fig. 5, a preferred form of circuits and apparatus for sending by the circuits of Figs. 3 and 3a and receiving by the inductor coils of Fig. 2 is disclosed.

Referring to Fig. 4, the microphone is indicated by the reference character M, while the carrier generator, modulator, calling current generator and power amplifier are indicated conventionally at TA, since, as stated above, these latter devices form no part of my present invention. The microphone M is preferably carried during non-communicating periods in a rack, not shown, and out of which it may be lifted when it is desired to establish a telephone conversation in order that it may be brought close to the person speaking. To facilitate the handling of the microphone M, it is mounted on a handle 15 which is adaptable to be manu-

ally operated to any one of three positions which I shall term "normal", "communicating", and "calling", these three positions being indicated by dotted lines in the drawing. As shown 5 schematically, two circuit controlling contacts 16 and 61 are operatively connected with the handle 15 and are moved to the three positions designated by the numerals 1, 2, and 3, in response to the normal, communicating and calling positions, respectively. A push button 17 is also mounted on the handle 15, the contact member 18 of which is adapted to make engagement with a contact 19 when the push button is depressed and to break engagement therewith when the push button is released. A circuit controlling contact 20 is associated with the microphone M and is biased by its own spring action to make engagement with a stationary contact 21 but is normally held out of 10 engagement therewith through the medium of an insulated member 22 mounted on the microphone M, the arrangement being such that with the microphone M placed in the rack, the member 22 forces the spring 20 to the left in the drawings and out of engagement with the contact 21, but that with the microphone M removed from the rack, that is, moved to the right in the drawings, the member 22 disengages the contact 20 and that member springs into 15 engagement with contact 21 to complete the connection therethrough. It will be noted that the handle 15 may be operated to any one of its three positions with the microphone remaining in the rack, as well as when it is lifted out 20 of the rack.

The microphone M is connected with the input of the apparatus TA over wires 10 and 11, while wires 12 and 13 connect the output of the apparatus TA with the winding 14 of a transformer T, a front contact 17-18 of a directional relay DR to be referred to later being interposed in the wire 12, and a second front contact 75-76 of the relay being interposed in wire 13. The circuit for rendering the transmitting apparatus 25 active to supply a calling frequency current is shown completed by the contact 61 being moved to its No. 3 position to connect the two wires 62 and 63. It is deemed sufficient for this description to say that frequencies corresponding to 30 voice frequencies developed in the microphone will be applied to the carrier, which in this instance is of 7000 cycles per second, for modulating the carrier, the carrier and the lower side band will be suppressed and the upper side band 35 will be amplified to a relatively high energy level and supplied to the winding 14 of the transformer T, the winding 14 being in turn effective to induce electromotive forces of corresponding frequencies in transmitting circuits to be described more fully hereinafter. Completing the 40 connection between the wires 62 and 63 by operating the handle 15 to the calling position to move the contact 61 to its No. 3 position will cause the apparatus TA to produce a calling or 45 code frequency current which in this instance is of 7800 cycles per second and which current will be amplified to a relatively high energy level and supplied to the winding 14 and in turn supplied to the transmitting circuits.

70 The equipment of Fig. 4 includes a directional relay DR and a tuning relay R both of which are shown as direct current neutral relays adaptable of being energized by direct current from any convenient source such as a battery, not 75 shown. The directional relay DR is provided

with two energizing circuits both of which are easily traced and one of which includes the No. 2 position of the contact 16 and the push button 17 depressed, and the other of which includes the No. 3 position of the contact 16 only. That is 5 to say, the directional relay is deenergized under the normal position of the microphone handle 15, and is energized when the handle 15 is moved to the communicating position and the push button 17 is depressed, and also when the handle 15 is moved to the calling position. The tuning relay R is provided with two simple energizing circuits one of which includes the contact 20-21, and the other of which includes the contact 23 of a common spring return push 10 button 24. Hence, the tuning relay R is normally deenergized and is energized whenever the microphone M is taken out of the rack and the contact 20-21 is closed, and may also be energized while the microphone M remains in the 15 rack by depressing the push button 24. The function of the tuning relay R and the directional relay DR will appear later in the description. 20

In Fig. 4, the inductor coils C1 and C2 are 25 connected in parallel across the winding 67 of the transformer T by either one of two circuits, the first circuit being traced from the top terminal of the coils over a back contact 65-66 of the tuning relay R, condenser 68, lower portion 30 of the winding 67, and wire 69 to the lower terminals of the inductor coils. The parts of this circuit are so proportioned and adjusted as to tune the circuit to resonance at the calling frequency of 7800 cycles and to give the circuit 35 a power factor of say 1.0%. At such time as the tuning relay R is energized to lift the contact finger 65 out of engagement with the back contact 66 and into engagement with the front contact 70 the inductor coils C1 and C2 are 40 connected across the full portion of the winding 67 through a condenser 71. The condenser 71 and the full portion of the winding 67 are so proportioned as to tune the circuit to resonance 45 at about the mid-voice frequency and to raise the power factor of the circuit to about 5.0%, and, hence, make the circuit effective to pass a band of frequencies equal to the desired voice frequency range, which in this instance extends 50 from 7600 to 8800 cycles.

Currents supplied by the coils C1 and C2 to the winding 67 of the transformer T will induce electromotive forces of corresponding frequencies in the winding 14 of that transformer and which winding is normally connected with the input of 55 the receiving apparatus RA through the band-pass filter F1, the back contacts 75-72 and 77-73 of the directional relay DR being interposed in the connection. The output side of the receiving apparatus RA is connected with a 60 loudspeaker LS.

It follows that with relays R and DR both released the inductor coils C1 and C2 are included in a low power factor circuit sharply tuned to the calling frequency, and the current 65 supplied by these inductor coils to the winding 67 of the transformer T will be passed to the input of the receiving apparatus over back contacts of the directional relay and through a band-pass filter F1. With relay R picked up 70 and the directional relay DR released, the inductor coils C1 and C2 are included in a circuit having a relatively high power factor and tuned to resonance at the mid-voice frequency, and the telephone current will be effectively re- 75

ceived by the inductors and supplied by them to the transformer winding 67 and thence passed to the input of the receiving apparatus. With the directional relay DR picked up the winding 14 of the transformer T will be transferred from the receiving apparatus to the output of a transmitting apparatus and current will be supplied to the inductor coils C1 and C2 for inducing an electromotive force in the traffic rails and the neighboring paralleling conductors, the coils being tuned to the calling frequency when the tuning relay R is released and tuned to pass the voice frequency band when the tuning relay R is picked up. In Fig. 4, the inductors C1 and C2 are shown connected in parallel. It is clear, however, they may be connected in series if desired.

In Fig. 5, the microphone M is connected over wires 51 and 58 with the input of the amplifier-modulator AM of the transmitting apparatus TA. The output of the amplifier-modulator AM is supplied over wires 39 and 40 to the input of the power amplifier PA which preferably includes a pair of power tubes connected in the conventional push-pull arrangement. The output of the power amplifier PA is connected with the primary winding 9 of the output transformer T1 over wires 41 and 42, the secondary winding 8 of the transformer T1 being interposed in a sending circuit such as described in Fig. 3. The input of the amplifier-demodulator AD of the receiving apparatus RA is connected with inductor C1—C2 through a band-pass filter BPF and the output of this amplifier-demodulator is supplied to a transformer T2 and, in turn, to the loudspeaker LS. A power unit PU consisting of two motor-generators or dynamos DM1 and DM2 is provided. The motor 43 of the motor-generator DM1 is constantly supplied with power from any convenient source of current such as a battery, not shown, the two terminals of the source being indicated at B32 and N32. The motor 64 of the motor-generator DM2 is normally inactive and is supplied with current from the source B32—N32 when the relay DR1 is energized and its front contact 44 is closed. The generator 45 of motor-generator DM1 is connected with the plate circuits of the tubes for the amplifier-demodulator AD of the receiving apparatus over a circuit including positive terminal of generator 45, wire 46, back contact 47 of relay DR1, wire 48, plate circuits of the tubes of the amplifier-demodulator and thence over wire 49 to the negative terminal of the generator 45. Energization of the relay DR1 in a manner to be shortly described to open its back contact 47 and close its front contact 50 transfers the generator 45 to the plate circuits for the tubes of the amplifier-modulator AM of the transmitting apparatus TA. This circuit can be traced from the positive terminal of generator 45 over wire 46, front contact 50 of relay DR1, wire 51, plate circuits of the amplifier-modulator AM and thence by wires 52 and 49 to the negative terminal of generator 45. When the relay DR1 is energized and its front contact 53 is closed, the generator 45 of motor-generator DM1 and the generator 54 of motor-generator DM2 are connected in series for supplying voltage to the plate circuits for the tubes of the power amplifier PA of the transmitting apparatus. This circuit is from the positive terminal of generator 45, wire 46, front contact 53 of relay DR1, wire 55, generator 54, wire 56, plate circuit for the power tubes, and

thence by wires 52 and 49 to negative terminal of generator 45. The relay DR1 is provided with an energizing circuit similar to that described for the relay DR of Fig. 4, and which circuit is controlled by the push button 17 and 5 the contact 16 associated with the microphone handle 15.

Referring again to Fig. 1, the transmitting apparatus TA on the caboose 31 is arranged for sending current by the circuit of Fig. 3, and the receiving apparatus RA on the locomotive is arranged to pick up energy through the medium of the inductor coils of Fig. 2. Assuming the train crew in the caboose desires to telephone to the crew on the locomotive, the equipment in the caboose is manipulated to render the transmitting apparatus effective to supply telephone current to the track rails. As a result of such current supplied to the rails at the caboose, current flows in the rails of track RT1 in both directions from the caboose. Along the zone extending from the caboose, induction of the rails to the line wire L induces an electromotive force in the line wire. This transfer of energy is illustrated in Fig. 1 by broken lines with arrows added to indicate that the energy transferred is from the rails to the line. It is noted that this transfer of energy from the rails to the line wire is effected notwithstanding the fact that section 34 of the line wire L adjacent the caboose is distant from the rails. This is because the communication current in the rails is still at a relatively high level opposite the adjacent sections 33 and 35. The electromotive force induced in the line wire L creates a flow of current in the line wire in both directions. The attenuation of this current in the line wire is relatively low so that at a distant point such as section 37 adjacent the locomotive 32, the current in the line wire induces an electromotive 35 force in the rails 1a and 1b of track RT1 and also in the rails 2a and 2b of the track RT2. This energy transfer is illustrated by dotted lines with arrows placed thereon to indicate that the transfer is from the line wire to the rails. The 40 electromotive force thus induced in the rails adjacent the section 37 of the line wire causes a current to flow in the rails in multiple and which current is relatively large with respect to the original current remaining in the rails 1a and 1b. 50 The inductor on the locomotive 32 inductively receives an electromotive force the value of which is the sum total of that produced by the current in the rails 1a and 1b and also by the current in the rails 2a and 2b. It is to be noted 55 that the current supplied to the rails 1a and 1b at the caboose 31 may induce an electromotive force in the rails of the adjacent track RT2 and a current set up in these latter rails. The attenuation of such current in the rails 2a and 2b is 60 relatively large due to the ballast resistance and is negligible adjacent the locomotive 32. It follows that the transmission of communication current from the caboose to the locomotive consists of four stages of energy transfer. First, 65 transmitting apparatus TA to the track rails to create current which flows in the rails 1a and 1b, and which current is relatively large close to the caboose but which has a relatively large attenuation due to the ballast resistance. Second, induction from the rails along this zone of relatively large rail current to the line wire L to cause current to flow in the line wire and the attenuation of which current is relatively 70 low. Third, induction from the line wire L to 75

the track rails of both tracks at locations distant from the caboose which causes a rail current larger than the original current remaining in the rails at such distant locations. Fourth, induction from the rails to the receiving inductor mounted on the locomotive and which inductor is positioned for inductive relationship with the rails of the adjacent track as well as with the rails of the track occupied. It can be shown that at a locality where the ballast resistance is about 6 ohms per thousand feet of track, the line wire increases the received current about 14 times in the case of a freight train of 100 cars.

It is to be noted that with the caboose of the train of Fig. 1 provided with the sending circuit of Fig. 3, the current flowing in the return portion of the sending circuit along the caboose roof will flow in the same direction as that of the rail current beyond the caboose and opposite in direction to that flowing in the rails between the caboose wheels. This being so, the mutual induction effected by this return portion of the sending circuit on the line wire L will oppose the induction effected by the rail portion of the sending circuit on the line wire, and will be the larger of the two since the return portion is usually closer to the line wire. Although the rail currents beyond the caboose are much smaller than the current in the return portion of the sending circuit, yet because of their much longer exposure to the line wire, the effect of the current in the rails will be the larger. It is clear that with the locomotive 32 equipped with the sending circuit of Fig. 3a and the caboose equipped with inductor coils, communication current will be transferred from the locomotive to the caboose through the medium of the line wire L in a manner similar to that described above. Hence, if the caboose and locomotive are both provided with the equipment of Fig. 5 and the two train crews operate their respective equipments to the sending and receiving conditions, telephone communication between the caboose 31 and the locomotive 32 may be accomplished, the effective communication channel being over the line wire L. Furthermore, it is apparent that with the caboose 31 and the locomotive 32 both equipped with the equipment of Fig. 4 communication between these two locations may be accomplished with the line wire L serving as the effective communication channel. Best results have been found to occur when the inductor coils are mounted in the position of maximum induction to the track rails, and direct induction with the line wire is negligible. It is clear that line wire L will serve as an effective communication channel for a train operating on track RT2.

Figs. 6, 7, and 8 disclose apparatus effective to compensate the impedance of the line wire L for the communication current. The characteristic impedance for an open wire line wire of No. 10 gauge copper wire strung about 10 feet off the ground, a leakage of about one megohm and a distributed capacitance of about .002 microfarad per 1000 feet, will be approximately 575 ohms at 8000 cycles. The propagation constant will be of such value that the current will lose only about one-half of one per cent of its value per mile. To reduce the characteristic impedance and hence increase the flow of communication current in response to the electro-motive force induced at any point of the line wire and to maintain the propagation constant

at a value such that the attenuation of the current is less than one-half at a distance equal to the length of an ordinary freight train, the tuning devices of Figs. 6, 7, and 8 are useful. In Fig. 6, these tuning devices each consists of a 5 shunt condenser and a series condenser. At spaced locations the condensers 25, 26, and 27 are serially interposed in the line wire L, one at each location. Condensers 28, 29, and 30 are connected between the line wire L and ground 10 at the locations of the condensers 25, 26, and 27, respectively. It can be shown mathematically that with the line wire L of Fig. 6 an open wire of No. 15 gauge copper wire, condensers 25, 26, and 27 each of about 0.4 microfarad, condensers 15 28, 29, and 30 each of about 0.64 microfarad, and the tuning devices spaced about one mile apart, the reactance of the line wire L is tuned out and the characteristic impedance is substantially 20.5, 27.5, and 35 ohms at 7600, 8450, and 20 9300 cycles, respectively. The propagation constant at these frequencies is such that the currents have a value of about 50, 68, and 75 per cent of the original value at a distance of one mile. In other words, the tuning devices of 25 Fig. 6 are effective to reduce the average characteristic impedance of the line wire to about 28 ohms and approximately two-thirds of the communication current is left at a distance of 30 one mile from the point of induction. 30

The serial condensers 25, 26, and 27 of Fig. 6 may be omitted leaving the tuning devices to consist of the shunt condensers 28, 29, and 30 only. With such an arrangement and with each of the condensers 28, 29 and 30 of about 0.63 35 microfarad and spaced along the open wire line L about every 1670 feet, the characteristic impedance of the line will be about 32 ohms at 8000 cycles. The propagation constant for the line wire will be such that the current will be 40 about 92% of its original value at a distance of one mile from the point of induction.

In Fig. 7, tuning devices consisting of a resistor and a condenser are provided at spaced locations along the line wire, the resistor being 45 interposed between the line wire and ground and the condenser being serially connected with the line wire. It can be shown mathematically that with the line wire of Fig. 7 of No. 13 gauge copper wire, resistors 115, 116, and 117 each of 50 about 22 ohms, condensers 118, 119, and 120 each of about 0.36 microfarad, and the tuning devices spaced substantially three miles apart, the average characteristic impedance for the line wire will be about 27 ohms for frequencies ranging from 7600 to 9300 cycles. The propagation constant in this case will be of such value that the attenuation of the communication current at one mile distant from the point of induction will be about one-half. 60

Another possibility is disclosed in Fig. 8. Here each tuning device consists of a shunt condenser connected between the line wire and ground and two series condensers, the arrangement being such that the connection for the shunt condenser is at the mid-terminal of the two series condensers as will be readily understood by an inspection of Fig. 8. 65

I have found that tuning devices such as disclosed in Figs. 6, 7, and 8 and connected with an open wire line at selected points are effective to increase the flow of communication current and still maintain an attenuation such that over 50% of the current remains at a distance of one mile from the point of induction. 70 75

Although I have herein shown and described several forms of apparatus embodying my invention, it is understood that various changes and modifications may be made therein within the 5 scope of the appended claims without departing from the spirit and scope of my invention.

Having thus described my invention, what I claim is:

1. In combination with railway train-carried 10 communication equipment including a signaling device responsive to an alternating signaling current, an air core inductor of relatively large central area, said inductor mounted in a vertical plane on the roof of a vehicle of the train for inductively receiving electromotive forces due 15 to an alternating signaling current which flows in the traffic rails of the track occupied by the train and in the neighboring conductors parallel to said rails in multiple, and circuit means for 20 connecting the inductor with the communication equipment for actuating the signaling device in response to the electromotive forces induced in said inductor.

2. In a railway communication system comprising 25 train-carried receiving apparatus including a signaling device responsive to alternating current; a communication channel including the traffic rails of the track occupied by a train, the traffic rails of the tracks adjacent thereto, and line wires parallel therewith; and transmitting apparatus remote from the receiving apparatus including a source of alternating signaling current effective to supply to said channel current which flows in the several conductors thereof in parallel; a first and a second air core inductor of relatively large central area mounted on a vehicle of a train above the body of the vehicle, said inductors placed in a vertical plane one in advance of the other for inductively receiving electromotive forces due to 30 the signaling current flowing in the several conductors of the channel, and circuit means for connecting said inductors with the receiving apparatus for actuating the signaling device in 35 response to the combined energy of the electromotive forces induced in the inductors.

3. In combination with railway train-carried 40 communication equipment including transmitting apparatus capable of supplying a carrier current modulated with a signaling frequency and receiving apparatus capable of reproducing the signaling frequency of a modulated carrier current, a relatively large central area air core inductor coil mounted on the roof of a vehicle 45 of a train and in a vertical plane to induce an electromotive force in the rails of the track occupied and in neighboring conductors parallel to said rails when said inductor is connected to the transmitting apparatus, and to inductively receive electromotive forces due to modulated carrier current flowing in said rails and in the neighboring parallel conductors when said inductor is connected to the receiving apparatus, and train-carried control means to selectively 50 connect said inductor either to the transmitting apparatus or to the receiving apparatus.

4. In combination with railway train-carried 55 communication equipment including a signaling device responsive to an alternating signaling current, an inductor mounted on a vehicle of a train at a height above the track substantially equal to the horizontal distance between the track occupied by the train and an adjacent track, said inductor positioned to link a horizontal magnetic field transverse to the track for 60

inductively receiving electromotive forces due to an alternating signaling current which flows in each of the rails of said two tracks in parallel, and circuit means for connecting the inductor with the communication equipment for actuating the signaling device in response to the electromotive forces induced in said inductor. 5

5. In combination with railway train-carried 10 communication equipment including a signaling device responsive to an alternating signaling current, an inductor mounted on a vehicle of a train above the body of the vehicle and at a height above the track substantially equal to the horizontal distance between the track occupied by the train and an adjacent track, said inductor positioned to link a horizontal magnetic field transverse to the track for inductively receiving electromotive forces due to an alternating signaling current which flows in the train body and in each of the rails of said two tracks 15 in parallel and which forces add their effects, and circuit means for connecting the inductor with the communication equipment for actuating said signaling device in response to the electromotive forces induced in said inductor. 20

6. In a railway communication system comprising 25 train-carried receiving apparatus including a signaling device responsive to alternating current; a communication channel including the traffic rails of the track occupied by a train, the traffic rails of the tracks adjacent thereto, and line wires parallel therewith; and transmitting apparatus remote from the receiving apparatus including a source of alternating signaling current effective to supply to the channel current 30 which flows separately in each of the several conductors thereof; in combination with the above instrumentalities a train-carried inductor mounted on a vehicle of the train at a height substantially equal to the horizontal distance between the track occupied by the train and an adjacent track, said inductor mounted in a plane to link a horizontal magnetic field transverse to the track for inductively receiving electromotive forces due to the signaling current flowing in 35 the several conductors of the channel which forces are additive in their effects, and circuit means for connecting the inductor with the receiving apparatus for actuating the signaling device in response to the electromotive forces 40 induced in the inductor. 45

7. In a railway communication system comprising 50 train-carried receiving apparatus including a signaling device responsive to alternating current; a communication channel including the traffic rails of the track occupied by a train, the traffic rails of the tracks adjacent thereto, and line wires parallel therewith; and transmitting apparatus remote from the receiving apparatus including a source of alternating signaling current 55 effective to supply to the channel current which flows separately in each of the several conductors thereof; in combination with the above instrumentalities a train-carried air core inductor of relatively large central area mounted on a vehicle of a train above the body of the vehicle and in a vertical plane for inductively receiving electromotive forces due to the signaling current flowing in the several conductors of the channel and which forces are additive in their effects, and 60 circuit means for connecting the inductor with the receiving apparatus for actuating the signaling device in response to the electromotive forces induced in the inductor. 65

8. In combination with railway train-carried 70

telephone equipment including transmitting apparatus capable of supplying a carrier telephone current and receiving apparatus capable of reproducing the audio frequencies of a carrier telephone current, an inductor mounted on a vehicle of the train above the body of the vehicle and positioned in a plane to link a horizontal magnetic field transverse to the track for induction to the body of the vehicle and to the traffic rails of the track occupied by the train and the traffic rails of an adjacent track, a first circuit means to connect said inductor with the transmitting apparatus for inductively supplying a telephone current which flows in the train body and in the traffic rails of said tracks in parallel, a second circuit means to connect the inductor to the receiving apparatus for inductively receiving electromotive forces due to a carrier telephone current flowing in the train body and in the traffic rails of said tracks in parallel, and manually controlled means for governing said first and second circuit means.

9. A railway communication system comprising, a train including two spaced vehicles, means on one vehicle including a source of communication current and a circuit coupled to the track rails to cause communication current to flow in the rails in multiple from said vehicle, means on the other vehicle including a signaling device responsive to the communication current and a circuit coupled to the track rails for receiving an electromotive force due to communication current flowing in the rails in multiple, and a line wire disposed along the railway and so positioned with respect to the rails that the communication current flowing in the rails at said one vehicle induces current in the line wire by virtue of the mutual induction between the line wire and the rails and which line current induces a current in the rails adjacent said other vehicle by virtue of the mutual induction between the line wire and the rails.

10. A railway communication system comprising, a train including two spaced vehicles, means on one vehicle including a source of communication current and a circuit coupled to the track rails to cause communication current to flow in the rails in multiple from said vehicle, means on the other vehicle including a signaling device responsive to the communication current and a circuit coupled to the track rails for receiving an electromotive force due to communication current flowing in the rails in multiple, and a line wire disposed along the railway and so positioned with respect to the rails that communication current is transferred from the rails to the line wire adjacent said one vehicle solely by virtue of the distributed mutual induction between the rails and the line wire and is transferred from the line wire back to the rails adjacent said other vehicle solely by virtue of the distributed mutual induction between the line wire and the rails in multiple.

11. A railway communication system comprising, a train including two spaced vehicles, means on one vehicle including a source of communication current and a circuit coupled to the track rails to cause communication current to flow in the rails in multiple from said vehicle, means on the other vehicle including a signaling device responsive to the communication current and a circuit coupled to the track rails for receiving an electromotive force due to communication current flowing in the rails in multiple, and a line wire disposed along the railway and so posi-

tioned with respect to the rails that communication current is transferred from the rails to the line wire adjacent said one vehicle by virtue of the distributed mutual electromagnetic induction between the rails and the line wire and is transferred from the line wire back to the track rails adjacent said other vehicle by virtue of the distributed mutual electromagnetic induction between the line wire and the rails in multiple.

12. A railway communication system comprising, means at one location along the railway including a source of communication current and a circuit coupled to the track rails to cause communication current to flow in the rails in multiple in both directions from said one location, said rails characterized by relatively high attenuation for the communication current, a line wire extending along the railway and so positioned with respect to the rails that the communication current induces current in the line wire by virtue of the distributed mutual induction between the line wire and the rails adjacent said one location, said line wire characterized by a relatively low attenuation for the communication current whereby the current in the line wire induces current back in the rails at locations remote from said one location by virtue of the distributed mutual induction between the line wire and the track rails and which latter current is greater than the original current in the rails at such remote locations, and means remote from said one location including a signaling device responsive to the communication current and a circuit coupled to the track rails for receiving an electromotive force due to said latter communication current flowing in the rails.

13. A railway communication system comprising, a train including two spaced vehicles, transmitting apparatus located on one of the vehicles including a source of communication current and a circuit coupled to the track rails to cause communication current to flow in the rails in multiple in both directions from said vehicle, said rails characterized by relatively high attenuation for the communication current whereby a zone of influence extends from said vehicle in both directions with diminishing intensity, a line wire extending along the railway and so positioned with respect to the track rails that the communication current flowing in the rails induces current in the line wire by virtue of the mutual induction between the rails and the line wire adjacent said zone, said line wire characterized by relatively low attenuation for the communication current whereby the line current is effective to induce current in the rails adjacent the other vehicle by virtue of the mutual induction between the line wire and the rails and which latter current is greater than the original current remaining in the rails at said other vehicle, and receiving apparatus located on the other vehicle including a signaling device responsive to the communication current and a circuit coupled to the track rails.

14. A railway communication system comprising, a line wire disposed along a railway and said line wire due to construction conditions having sections where it is relatively close to the rails and other sections where it is relatively far from the rails, transmitting apparatus located on a first railway vehicle and including a current source and a sending circuit coupled to the rails to cause a communication current to flow in the rails in multiple in both directions from said vehicle to induce an electromotive force in the

line wire by virtue of the distributed mutual induction between the rails and the line wire adjacent such of its sections close to the rails in the vicinity of said vehicle for causing communication current to flow in the line wire, said line wire characterized by attenuation to the communication current relatively low compared to the attenuation of the rails to the current whereby the line current induces an electromotive force in the rails by virtue of the distributed mutual induction between the rails and the line wire adjacent its sections close to the rails remote from said first vehicle to cause communication current to flow in the rails which is greater than the original current at such remote distance from said vehicle, and receiving apparatus on a second railway vehicle remote from said first vehicle and including a signaling device responsive to the communication current and a circuit coupled to the rails.

15. A railway communication system comprising, a line wire disposed along the railway which due to construction conditions consists of sections relatively close to the track rails and other sections relatively far from the track rails, a train including two vehicles spaced relatively far apart, transmitting apparatus on one of the vehicles including a source of communication current and a circuit coupled to the track rails to cause communication current to flow in the rails in multiple in both directions from said one vehicle, said current effective to transfer communication current to the line wire by virtue of the mutual induction between the rails and the relatively close sections of the line wire in the vicinity of said one vehicle, said line communication current effective to transfer current to the rails by virtue of the mutual induction between the rails and the relatively close sections of the line wire in the vicinity of the other vehicle, and receiving apparatus on said other vehicle including a signaling device responsive to the communication current and an inductor mounted on the vehicle in inductive relation with the track rails.

45. A railway communication system comprising, a railway track, a train to travel on said track, means located on a vehicle of the train including a source of communication current and a circuit coupled with the track rails to cause communication current to flow in the rails in multiple in both directions from the vehicle, a line wire disposed along said railway for distributed mutual induction to the track rails for inductively receiving an electromotive force due to the current flowing in the rails to cause a corresponding current to flow in the line wire, and receiving apparatus remote from said vehicle including a signaling device responsive to said communication current and a circuit effectively coupled with said line wire.

17. A railway communication system comprising, a railway track, a train to travel on said track, means located on a vehicle of the train including a signaling device responsive to a communication current and an inductor mounted on the vehicle in inductive relation with the track rails for receiving an electromotive force due to communication current flowing in the rails in multiple, a line wire disposed along said railway for distributed mutual induction to the track rails for inducing an electromotive force in each rail due to communication current flowing in the line wire for causing communication current to flow in the two rails in multiple, and means re-

5. mote from said vehicle including a source of communication current and a circuit effectively coupled with the line wire for causing communication current to flow in the line wire.

18. A railway communication system comprising, transmitting apparatus located on one vehicle of a train and including a current source and a sending circuit effectively coupled to the track rails to cause a communication current to flow in a first rail circuit consisting of the two rails in multiple to each side of the vehicle and ground return, receiving apparatus located on another vehicle of the train spaced apart from said one vehicle and including a signaling device responsive to the communication current and a receiving circuit effectively coupled to the track rails to receive an electromotive force due to communication current flowing in a second rail circuit consisting of the two rails in multiple to each side of said other vehicle and ground return, and a line wire extending along the railway for distributed mutual induction to the rails for inductively receiving an electromotive force due to the current in the first rail circuit to cause communication current to flow in the line wire which induces an electromotive force in the rails to cause communication current to flow in said second rail circuit.

19. A railway communication system comprising, a multiple track railway, transmitting apparatus located on one vehicle of a train occupying one of said tracks and operative to cause a communication current to flow in the rails of that track in multiple in both directions from said vehicle, said rails characterized by relatively high attenuation for such current, a line wire disposed along said railway in an inductive relation with the rails of said tracks for inductively receiving an electromotive force due to such current in the rails of said one track to cause communication current to flow in the line wire, said line wire characterized by relatively low attenuation for the communication current whereby the line current induces an electromotive force in the rails of each track at points remote from said one vehicle and which electromotive force causes current to flow in the rails of all the tracks in multiple, and receiving apparatus located on a second vehicle of the train remote from said one vehicle including a signaling device responsive to such communication current and an inductor, and said inductor mounted in a vertical plane above the body of the vehicle in an inductive relation with the rails of the adjacent tracks as well as with the rails of the track occupied to actuate said signaling device by the electromotive force received due to the current in the rails of all the tracks in multiple.

20. A railway communication system comprising, a multiple track railway, transmitting apparatus located on one vehicle of a train occupying one of said tracks and operative to cause a communication current to flow in the rails of that track in multiple in both directions from said vehicle, said rails characterized by relatively high attenuation for such current, a line wire disposed along said railway in an inductive relation with the rails of said tracks for inductively receiving an electromotive force due to such current in the rails of said one track to cause communication current to flow in the line wire, said line wire characterized by relatively low attenuation for the communication current whereby the line current induces an electromotive force in the rails of each track at points remote from

communication equipment including transmitting apparatus located on a vehicle of a train and capable of delivering a communication current to a pair of output terminals, means to connect one of the output terminals with the journal bearing of a wheel at one end of the vehicle, a return conductor disposed lengthwise along the top of the vehicle, means including a vertical conductor at said one end of the vehicle 5 to connect said return conductor with the other of said output terminals, and means including a vertical conductor at the opposite end of the vehicle to connect said return conductor with the journal bearing of a wheel at said opposite 10 end of the vehicle whereby said current is caused to flow in the track rails between said wheels.

27. In combination with railway train-carried communication equipment including transmitting apparatus located on a vehicle of a train 20 and capable of delivering a carrier frequency communication current to a pair of output terminals, means to connect the journal bearings of a pair of wheels at one end of the vehicle in parallel with one of said output terminals, a 25 return conductor disposed lengthwise along the top of the vehicle, means including a vertical conductor at said one end of the vehicle to connect said return conductor with the other of said output terminals, and means including 30 a vertical conductor at the opposite end of the vehicle to connect the journal bearings of a pair of wheels at said opposite end in parallel with said return conductor whereby said current is caused to flow in the two rails between 35 said two pair of wheels in parallel.

28. In combination with railway train-carried communication equipment including transmitting apparatus located on a vehicle of a train and capable of delivering a carrier frequency communication current to a pair of output terminals, means to connect a pair of wheels at one 40 end of the vehicle in parallel with one of said output terminals, a return conductor disposed lengthwise along the top of the vehicle, means including a vertical conductor at said one end of the vehicle to connect said return conductor with the other of said output terminals, and means including a vertical conductor at the opposite end of the vehicle to connect a pair of wheels at 45 said opposite end in parallel with said return conductor whereby said current is caused to flow in the two rails between the two pair of wheels

in parallel and inductive reactance of the rails is relatively high.

29. In combination with railway train-carried communication equipment including transmitting apparatus located on a vehicle of a train and capable of delivering a carrier frequency communication current to a pair of output terminals, means to connect the journal bearings of a pair of wheels at one end of the vehicle in parallel with one of said output terminals, a return 10 conductor disposed lengthwise along the vehicle and relatively high above the top of the rails, means to connect one end of said return conductor with the other of said output terminals, other means to connect the journal bearings of a 15 pair of wheels at the other end of the vehicle in parallel with the other end of said return conductor, and means to insulate each of said journal bearings from its associated journal box.

30. In combination with railway train-carried communication equipment including transmitting apparatus located on a vehicle of a train and capable of delivering an alternating communication current to the primary winding of an output transformer; a sending circuit on said vehicle 20 comprising a first conductor disposed lengthwise along the top of the vehicle, a second conductor disposed substantially vertical from a journal bearing of a wheel at one end of the vehicle to said first conductor and a third conductor disposed substantially vertical from a journal bearing of a wheel at the other end of the vehicle to said first conductor; and means to interpose the secondary winding of the output transformer in 25 said second conductor.

31. In combination with railway train-carried communication equipment comprising, transmitting apparatus on a vehicle of a train capable of delivering an alternating communication current and including a sending circuit consisting of a 30 return portion disposed lengthwise along the top of the vehicle and vertical portions at each end of the vehicle to connect with vehicle wheels one at each end, receiving apparatus responsive to such communication current and including an 35 inductor mounted on the vehicle above the vehicle body and in a vertical plane to link a horizontal magnetic field transverse to the track rails, and circuit means operative to selectively render said transmitting apparatus and said receiving 40 apparatus active.
